RANGE BURNER

Rallston M. Sherman, Glastonbury, and Frederick F. Neumann, West Hartford, Conn., assignors to The Silent Glow Oil Burner Corporation, Hartford, Conn., a corporation of Connecticut

Application December 20, 1929, Serial No. 415,470

14 Claims. (Cl. 158—87)

This invention relates to burners of the type supplied with oil or other hydrocarbon fuel in liquid form, the oil being vaporized within the burner and then burned with a suitable mixture of air. These burners are commonly provided with one or more combustion chambers having perforated tubular walls through which air enters to mix with fuel vapor ascending from a fuel space, the latter in the form of a fuel groove or trough at the bottom of the chamber, the mixture being burned in the combustion chamber and a blue flame issuing from the open upper end thereof.

In starting a burner of this type from a cold condition it is customary preliminarily to heat the burner walls and base before finally turning on the full continuing supply of liquid fuel so that some vaporization of the liquid fuel will take place when it reaches the fuel space.

One common method of effecting such preliminary heating is to provide the fuel groove or trough with an asbestos or other wick which is first saturated with oil or other priming fluid and then lighted by a taper. After a short interval, when the temperature of the adjoining walls of the burner is sufficient to cause a vaporization of a portion of the liquid fuel reaching the fuel groove, the liquid fuel supply is turned on. As the temperature gradually rises, the walls of the fuel groove and adjoining fuel passages become more highly heated and an increasingly greater proportion of the fuel reaches the fuel groove in vaporized form, and finally, after the lapse of a substantial interval, the fuel reaching the fuel space or spaces is completely vaporized and an intensely hot blue flame results.

The time required for the preliminary heating and before the burner can be brought up to its full heating capacity, which may be termed the starting interval, has heretofore been quite substantial, due in large part to the fact that in the initial stages of starting a substantial part of the oil reaches the fuel groove in liquid form, retarding complete combustion and causing the rise in temperature required for complete vaporization to take place very gradually. The oil which reaches the fuel groove or grooves in liquid form also tends to incomplete combustion, leaving deposits of unconsumed carbon which, in the course of time, build up and clog the fuel grooves and connecting ducts, passages and pipes.

One object of the present invention is to substantially reduce the time required for starting, there being provided such an arrangement for fuel delivery to the fuel space that the heated

walls of the burner, and particularly during the starting interval, will be most fully effective to vaporize the fuel on its delivery to the burner and before reaching the fuel groove. Accordingly, even during the early part of the starting interval, a greater proportion of the fuel in vaporized form and a lesser proportion in liquid form reach the fuel groove, so that the proportion of fuel vaporized and the intensity of the flame increase at a more rapid rate than has heretofore been possible, and the time within which full vaporization is had and the full capacity of the burner reached is materially shortened.

Since this materially reduces the amount of liquid fuel which reaches the fuel grooves and the interconnecting ducts or passages during the starting interval, the accumulations of carbonized material are materially lessened and the cleaning of fuel grooves and passages is required to be performed less often. Furthermore, such deposit of carbon as may take place occurs in locations where it may be readily removed.

In the illustrated embodiment of the invention, this object is had by providing a relatively wide flow plate in close adjacent heat-conducting relation to the fuel space. The fuel supply is connected to cause the liquid fuel to travel over this heated flow plate in a relatively thin film and for a substantial distance before reaching the fuel space under conditions most effective for vaporizing the liquid, any portion of the fuel vaporized through contact with the plate, however, passing directly and without hindrance to the fuel space.

The invention also has for its object the simplified construction of burners of the type referred to and an arrangement such that the surfaces requiring to be cleaned can be readily uncovered and exposed.

These and other objects of the invention will be best understood by reference to the following description when taken in connection with the accompanying illustration showing one specific embodiment thereof, while its scope will be more particularly pointed out in the appended claims.

In the drawing:

Fig. 1 is a plan view of a burner embodying one form of the invention, the perforated walls for the combustion chambers and the cover plate supporting the inner chimney being partly broken away to better show the construction of the base member;

Fig. 2 is a vertical sectional elevation on the line 2—2 in Fig. 1; and

Fig. 3 is a sectional elevation on the line 3—3 in Fig. 1.

Referring to the drawing and to the embodiment of the invention which is submitted for illustrative purposes, the burner is provided with a base member 1 comprising a casting having an outer annular plate 3 and an inner annular concentric plate 5 connected one to the other by a series of webs 7, herein four in number, and providing for an annular air admission space 9 between the plates.

The inner plate 5 is provided with a central air admission opening 11 surrounded by an upturned, ring-like flange 13, the outer edge of the inner plate 5 having also an upturned, ring-like flange 15 spaced from but concentric with the flange 13.

The flanges 13 and 15, together with the bottom plate 5, form a relatively wide annular compartment or channel, on the bottom of which there is provided a raised arc-shaped lip 17 separating the compartment into an outer fuel space defined by the groove 19 and an inner vaporizing space having a preferably relatively wide, flow plate bottom 21 (Fig. 1). The fuel supply is delivered to the bottom of the vaporizing space by the pipe connection 23 through an opening 25 in the bottom of the flow plate. The raised lip 17, which separates the vaporizing space and flow plate from the fuel groove, constitutes a baffle which prevents direct travel of the liquid fuel from the fuel supply opening 25 into the fuel groove, but preferably permitting its flow thereto by a more or less prolonged path. For this purpose it is extended for a substantial distance at either side of the fuel supply opening 25, and herein to a point nearly 180 degrees away, where it is cut away at 27 to leave a free, unobstructed flow passage from the plate to the fuel groove through which any portion of the fuel remaining in liquid form may flow into the fuel groove without hindrance or the building up of any accumulated body of liquid on the flow plate.

The top of the vaporizing chamber is closed, except for the direct escape of vaporized fuel to the combustion chamber, by a removable annular cover plate 29 seated on the upper edge of the flange 13 and provided with a downwardly extending sleeve 31 which fits within the flange and positions the cover plate thereon. The walls of the cover plate extend outwardly and herein also downwardly over the vaporizing compartment and the annular lip, but are spaced vertically from the latter to provide an annular passage from the vaporizing compartment to the fuel space and combustion chamber so that any vaporized fuel may pass directly over the lip between the latter and the cover plate into the fuel groove and combustion chamber.

While the annular passage indicated may be of uniform cross-sectional area, herein the lip 17 is shown of slightly decreasing height (Fig. 2) from a point adjacent the fuel supply passage 25 to the flow passage or opening 27, so that the annular passage between the vaporizing and combustion chambers is of increasing cross-sectional area from the point where the fuel is delivered to a point at the flow passage 27 where only liquid fuel may pass into the fuel groove.

The peripheral edges of the cover plate are spaced from the inner walls of the flange 15 to provide an annular space through which the fuel space opens into the combustion chamber, and is provided with an upturned annular flange 33 within which there is secured a perforated sheet metal cylinder 35. A similar but larger concentric

cylinder 37 is removably seated on the outer shouldered edge of the upright flange 15, so that there is provided between the two cylinders the combustion chamber 39 opening at the bottom into the fuel space 19. It will be understood that the perforations in the sheet metal cylinders are distributed throughout substantially the entire surface thereof, a small perforated area only being shown in Fig. 2. It will also be understood that these perforations may be of any shape, size or arrangement to provide suitable air admission openings for the combustion chambers.

In the illustrative embodiment of the invention there is also provided an outer fuel groove 41 formed between the upright annular spaced concentric flanges 43 and 45 on the outer plate 3. Concentric spaced perforated sheet metal cylinders 47 and 49 are removably seated on the shouldered edges of the flanges 43 and 45 providing between them the combustion chamber 51. The outer fuel groove 41 is connected to the inner fuel groove 19 by means of the supply ducts 53 (Figs. 1 and 3) formed in the webs 7.

A removable annular cover plate 55 is provided with its edges resting upon the tops of the sheet metal cylinders 37 and 49 to close the top of the annular air space therebetween, and a disk-shaped closure plate 57 with its edges resting on the upper edges of the cylinder 35 is similarly provided to close the top of the central air chamber, leaving annular openings at the tops of the two combustion chambers 51 and 39 for the escape of the products of combustion. The closure plates 55 and 57 may, if desired, be provided with one or more apertures to permit the partial escape of the air therethrough.

In the operation of the burner, the latter is preliminarily heated either by igniting asbestos wicks (not herein shown) positioned in the fuel grooves and saturated with oil admitted through the supply pipe 23, or in any other desired manner. After the burner has been preliminarily heated, liquid fuel is then admitted through the supply pipe 23 under the regulation of any of the usual feeding devices. These commonly provide for the flow of fuel from the feeding device at some definite level, which may be accurately regulated, so that the flow of fuel may be maintained at a predetermined level over the flow plate, and a flow maintained of relatively shallow depth spreading over the flow plate in more or less film-like form. Such regulating devices are of the usual and common construction and are not herein shown.

The liquid fuel on leaving the supply passage 25 is caused to pass over the flow plate and to travel entirely around the same to the passage 27 before it is allowed to enter the fuel groove in liquid form. The flow plate is in close heat-conducting relation to the fuel groove so that the heat from the flame maintained in the fuel groove is transmitted directly thereto and is effective for vaporizing the liquid fuel in its passage over the flow plate. Any vaporized fuel passes directly up over the lip 17 into the fuel space and combustion chamber, where it mingle with the air and is immediately effective for promoting the combustion therein and raising the temperature of the burner and of the flow plate itself. This process quickly builds up the intensity of the flame and accelerates the temperature rise of the base member, so that a point is very soon established where all the liquid fuel delivered to the flow plate is vaporized before reaching the gate or passage 27 and all of it is delivered to the fuel

space in the form of vaporized oil. The full capacity of the burner is thereby quickly established, the starting interval very materially reduced, and the amount of liquid oil reaching the inner and outer fuel grooves subject to incomplete combustion is also materially reduced.

The cylinder 35 is preferably held fixed on the cover plate 29, as by a close frictional fit thereon, so that it may be utilized to lift the plate from the flange 13. By removing the cover plate and the cylinders 31, 41 and 49, the top of the entire base is opened and both the inner and outer fuel grooves may be readily inspected and cleaned, as well as the connecting ducts or passages 53.

For simplicity, a single burner unit only is shown, but the same constructional features may be embodied in one or more duplicate units, the generally annular base member 11 being connected to the corresponding base member of the other unit or units by webs integrally cast therewith or by other connections.

While we have herein shown and described for the purpose of illustration one specific embodiment of the invention, it is to be understood that the latter is not limited to the specific details of construction and relative arrangement herein shown, but that extensive deviations may be made therefrom without departing from the spirit of the invention.

We claim:

1. A burner comprising an annular trough body having a central opening therethrough and having a dividing wall, the latter comprising a raised arc-shaped lip forming inner and outer channels; fuel supply means communicating with the inner channel back of said arc-shaped lip, an annular cover plate having a portion closely interfitting with and supported by the inner wall of said trough and having a flange overlying the inner channel in spaced relation to the bottom wall of said inner channel and to the dividing wall to form a relatively narrow opening therebetween, a foraminous chimney erected on and supported by the overhanging peripheral edge of the flange, and a second foraminous chimney erected at the outer side of the trough.

2. A burner comprising an annular trough-shaped body having a central opening therein and having a dividing wall forming inner and outer channels; fuel supply means communicating with the inner channel back of said dividing wall, the latter having a relatively remote passage for the flow of liquid fuel from the inner to the outer channel, an annular cover plate having a formation closely interfitting with and supported by the inner wall of said trough and having a flange overlying the inner channel in spaced relation to the bottom wall of said inner channel and to the dividing wall to form a relatively narrow opening therebetween, a foraminous chimney erected on and supported by the overhanging peripheral edge of the flange, and a second foraminous chimney erected at the outer side of the trough.

3. A burner of the class described having spaced, concentric, tubular wall members providing between them a combustion chamber, a bottom plate having spaced inner and outer concentric flanges presenting between them a broad annular channel; said plate having a supply opening within said inner flange, a removable cover plate supported by and presenting a formation closely interfitting with said inner flange and having an air opening cooperatively related to the opening in said bottom plate, said cover plate

overlying said channel in spaced relation to the walls of said bottom plate and having its outer peripheral edges spaced from said outer flange to provide an uncovered portion for said channel substantially aligned with said combustion chamber, the inner one of said tubular members being supported by the peripheral edge of said cover plate, a fuel supply opening in the bottom of said channel, a barrier between said fuel supply opening and said uncovered portion of the channel permitting the direct passage thereto of vaporized fuel, and a flow passage around said barrier relatively remote from said fuel opening.

4. A liquid fuel burner having concentric combustion tubes forming inner and outer combustion chambers, a base having upstanding walls providing an inner, relatively wide, annular, fuel chamber and a separate laterally spaced, outer, relatively narrow, annular open, fuel chamber surrounding said inner chamber and beneath and opening into the outer combustion chamber, said base having an air passage between the chambers and also within the inner chamber, ducts connecting said inner and outer chambers, a removable annular cover plate resting on said base and having its walls extending outwardly over said inner chamber from the inner wall thereof and extending also downwardly but having its periphery spaced from the opposite upstanding wall of said chamber and from the underlying walls of the base to partially cover said chamber, providing an inner vaporizing space beneath the cover plate and an uncovered fuel space beneath and communicating with the inner combustion chamber, said cover plate having means adjacent its periphery to support and position a combustion tube, and means for introducing fuel from below to the bottom of said covered vaporizing space, said inner fuel chamber being formed to impede the flow of unvaporized liquid fuel from said vaporizing space to said uncovered fuel space while permitting the free passage of vaporized fuel thereto.

5. A liquid fuel burner having combustion tubes forming inner and outer combustion chambers, a base having an inner, relatively broad, continuous, fuel chamber and a separate, laterally spaced, open, outer, relatively narrow, continuous, fuel chamber surrounding said inner chamber and beneath and opening into the outer combustion chamber, ducts connecting said inner and outer chambers, a covering wall extending over one side of said inner chamber but having its overhanging edges spaced from the opposite side of said chamber and from the underlying walls of the base to partially cover said chamber, providing therein a vaporizing space beneath the covering wall but leaving an uncovered fuel space beneath and communicating with the inner combustion chamber, and means for introducing fuel from below to the bottom of said vaporizing space, said inner chamber having means to impede the flow of unvaporized liquid fuel from said vaporizing space to said uncovered fuel space while permitting the free passage of vaporized fuel thereto.

6. A liquid fuel burner having combustion tubes forming inner and outer combustion chambers, a base having an inner, relatively broad, continuous, fuel chamber and a separate, laterally spaced, open, outer, relatively narrow, continuous fuel chamber surrounding said inner chamber and beneath and opening into the outer combustion chamber, ducts connecting said inner and outer chambers, a covering wall extend-

ing over one side of said inner chamber but having its overhanging edges spaced from the opposite side of said chamber and from the underlying walls of the base to partially cover said chamber, providing therein a vaporizing space beneath the covering wall but leaving an uncovered fuel space beneath and communicating with the inner combustion chamber, means for introducing fuel from below to the bottom of said vaporizing space, and a raised wall on the bottom of the inner chamber between the fuel introducing means and the uncovered fuel space to impede the flow of unvaporized liquid fuel from said vaporizing space to said uncovered fuel space while permitting the free passage of vaporized fuel thereto.

7. A liquid fuel burner having a plurality of combustion tubes forming between them a combustion chamber and an inner air chamber with in the inner tube, a base having a broad, horizontally arranged, endless, fuel channel with an air admission opening within the inner wall thereof, a removable covering wall having a formation closely interfitting with the inner wall of said channel extending from the inner side of said fuel channel but having its peripheral edges spaced from the outer side thereof and from the underlying walls of the base to partially cover said channel and presenting a formation interfitting with and supporting the inner combustion tube, providing therein a vaporizing space beneath the covering wall and beneath the inner air chamber but leaving an uncovered vapor-distributing space beneath but communicating with the combustion chamber and surrounding the vaporizing space, means for introducing liquid fuel from below to the bottom of said covered vaporizing space, and means to impede the direct flow of liquid fuel from the fuel introducing means in the vaporizing space to the vapor-distributing space while permitting the free passage of vaporized fuel thereto.

8. A burner of the class described having pairs of concentric, spaced, combustion tubes forming between them inner and outer combustion chambers and providing an intermediate air chamber between said combustion chambers and an inner air chamber within the inner tube, a base surrounded by said combustion tubes and having openings for admitting air to said air chambers, said base presenting laterally spaced, interconnected, open, vapor distributing channels terminating in upwardly directed delivery portions one surrounding the other, said portions being beneath and registering one with the outer and the other with the inner combustion chambers and opening into said air chambers, one of said channels being of greater width than the other channel to form a vaporizing portion positioned laterally within and communicating with the delivery portion of said wide channel and extending beneath one of said air chambers, a removable plate resting on the walls of the base to overlie a part of the wider channel, said plate covering said vaporizing portion and underlying said last-named air chamber and exposed to the heat from the walls thereof, means for supplying liquid fuel to said vaporizing portion beneath said cover plate, and means for impeding the flow of unvaporized liquid fuel from said vaporizing portion to the delivery portion of said wider channel, while permitting the free passage of vaporized fuel thereto.

9. A liquid fuel burner having combustion

tubes forming inner and outer combustion chambers, a base having an inner, relatively broad, continuous, fuel chamber and a separate, laterally spaced, open, outer, relatively narrow, continuous fuel chamber surrounding said inner chamber and beneath and opening into the outer combustion chamber, ducts connecting said inner and outer chambers, a covering wall extending over one side of said inner chamber but having its overhanging edges spaced from the opposite side of said chamber and from the underlying walls of the base to partially cover said chamber, providing therein a vaporizing space beneath the covering wall but leaving an uncovered fuel space beneath and communicating with the inner combustion chamber, means for introducing fuel from below to the bottom of said vaporizing space, and a raised wall on the bottom of the inner chamber between the fuel introducing means and the uncovered fuel space and having an opening at the opposite side of said inner chamber from the fuel introducing means to impede the flow of unvaporized liquid fuel from said vaporizing space to said uncovered fuel space, while permitting the free passage of vaporized fuel thereto.

10. A burner comprising an annular trough body having a central opening therethrough and having a low dividing wall forming inner and outer channels, a fuel supply means communicating with the inner channel, an annular baffle member having a base snugly fitting within the opening through the trough and having a flange overlying the inner channel in closely spaced relation to the dividing wall to form a narrow opening therebetween, a foraminous chimney erected on the peripheral edge of the flange, and a second foraminous chimney erected at the outer side of the trough.

11. In combination, an oil vapor burner, a base member, concentric inner and outer flanges forming an annular channel on the base member, an oil supply pipe terminating near the inner flange of said channel, and a removable cover plate resting upon the innermost flange, the said cover plate extending towards, but terminating short of said outer flange and having a depending flange at its outer edge extending nearly to the bottom of said channel, thereby providing a vaporizing chamber under said plate, and an outlet for fuel vapor therefrom.

12. A burner having a base member provided with concentric, inner and outer raised walls forming an annular channel and providing an air admission opening within the inner wall of said channel, a removable annular cover plate resting on the inner wall of said channel, said plate extending toward but terminating short of the outer wall of said channel to leave an uncovered portion thereof while providing a vaporizing space beneath said plate, said plate further having a depending outer portion extending below the upper edges of said raised channel-forming walls, there being provided a restricted outlet for the fuel vapor from said vaporizing space to said uncovered portion, a foraminous chimney positioned on the outer portion of said cover plate, a second foraminous chimney positioned on the outer wall of said trough, and a liquid fuel supply inlet near the inner part of said channel to supply liquid fuel beneath said cover plate.

13. A burner having a base member provided with concentric, inner and outer raised walls forming an annular channel and providing an air admission opening within the inner wall of said

channel, a removable annular cover plate resting on the inner wall of said channel, said plate extending toward but terminating short of the outer wall of said channel to leave an uncovered portion thereat while providing a vaporizing space beneath said plate, said plate further having a depending outer portion, a raised wall on the bottom of said channel cooperating with said depending portion of the cover plate to provide a restricted outlet for the fuel vapor from said vaporizing space to said uncovered portion, a foraminous chimney positioned on the outer portion of said cover plate, a second foraminous chimney positioned on the outer wall of said trough, and a liquid fuel supply inlet near the inner part of said channel to supply liquid fuel beneath said cover plate.

14. A liquid fuel burner having spaced, concentric, combustion tubes forming inner and outer combustion chambers with an intermediate air chamber and an inner air chamber enclosed within the inner tube, a base surmounted by said combustion tube and comprising an inner, radially broad, annular, base portion and an outer, relatively narrow, base portion spaced from and surrounding said inner base portion and having connections thereto at intervals, said base having openings between said connections for supplying

air to said intermediate air chamber and an opening within said inner base portion for supplying air to said inner air chamber, said inner and outer base portions having vaporizing and distributing passages including annular, inner and outer, vapor distributing portions in said respective base portions, beneath and opening into said inner and outer combustion chambers, respectively, and said connections having ducts connecting said vapor distributing portions, said vaporizing and distributing passages including also an open vaporizing portion in said broad, annular, base portion and communicating with said vapor distributing portions, a removable cover plate resting on said base beneath said inner air chamber and exposed to the heat from the walls thereof, said plate covering said open vaporizing portion to form therewith a vaporizing chamber but leaving uncovered the vapor distributing portion communicating with said inner combustion chamber, a raised ported wall on the bottom of the broad, inner base portion between the vaporizing chamber and the vapor distributing portion for the inner combustion chamber, and means to introduce liquid fuel to said vaporizing chamber.
